UNITED STATES PATENT OFFICE.

NAPOLEON F. X. BEAUREGARD, OF CHICAGO, ILLINOIS.

PULVERIZED-FUEL GAS-GENERATOR.

1,351,460.

Specification of Letters Patent. Patented Aug. 31, 1920.

Application filed May 21, 1917. Serial No. 169,942.

To all whom it may concern:

Be it known that I, NAPOLEON F. X. BEAUREGARD, a subject of the King of England, and a resident of the city of Chicago, in the county of Cook and State of Illinois, have invented certain new and useful Improvements in Pulverized-Fuel Gas-Generators; and I do hereby declare that the following is a full, clear, and exact description of the same, reference being had to the accompanying drawings, and to the numerals of reference marked thereon, which form a part of this specification.

This invention relates to a process of fuel supply particularly adapted for use with boilers involving the generation of a gas, wherein powdered fuel is fed through a feed pipe under pressure and after mingling with steam, is subjected to heat, causing the generation of the gas, and substantially vaporizing the entire quantity of fuel, and thereafter blown through an ejector with additional air preferably under pressure, into the furnace for combustion.

With the low grade of fuel which is obtainable in certain localities, it has been found extremely difficult to burn the same upon grates in the furnace of a boiler, but by my invention, the use of grates is entirely dispensed with and complete combustion of the fuel assured, with apparently no ash residue or, if any, of such a small amount as to be carried away by the chimney draft. In this type of installation, any kind of coal fuel may be used, and if not already in a fine or powdered state, may be passed through a crusher to reduce the coal to powdered form and thereafter used with a nozzle injector entirely obviating the necessity for grates and ash handling systems.

It is an object therefore of this invention to provide a process for burning powdered coal, utilizing steam and air under pressure and inducing a flow of the powdered fuel through a heating means, together with the steam and air before admission into the furnace for combustion.

It is also an object of this invention to provide a process of burning fuel involving the generation of gas from the fuel by blowing the fuel in a suspended or powdered form through a heated conveyer pipe.

and ejecting the product thus formed under pressure into the furnace of a boiler for combustion.

It is also an object of this invention to provide a process for burning coal wherein preheated powdered fuel and air are blown into a furnace under pressure causing instantaneous and complete combustion of the mixture to take place.

It is furthermore an important object of this invention to provide a fuel burning apparatus wherein powdered fuel is blown through a pipe by air under pressure and intermingled with steam and thereafter subjected to heat and finally forced through an injector together with additional air under pressure into the furnace for combustion.

Other and further important objects of the invention will be apparent from the disclosure in the drawings and specification.

The invention (in a preferred form) is illustrated in the drawings and hereinafter more fully described.

On the drawings:

Figure 1 is a diagrammatic view with parts broken away, and parts shown in section illustrating the adaptation of a system embodying the principles of my invention to a boiler and furnace therefor.

Fig. 2 is a central vertical section, with parts in elevation, through the powdered fuel mixing valve of the system.

Fig. 3 is a sectional detail on line 3-3 of Fig. 2.

Fig. 4 is a detail view on line 4-4 of Fig. 2.

Fig. 5 is a central horizontal longitudinal section through the ejector in the furnace.

Fig. 6 is a sectional detail showing the steam admission means of the apparatus.

Fig. 7 is a top plan view of the revolving rake member of the mixing valve.

Fig. 8 is a sectional detail showing the pivot bearing whereby the height of the rake member above the adjustable grid plates of the mixing valve may be adjusted.

Fig. 9 is a sectional detail, with parts in elevation, of the adjustable vanes on line 9-9 of Fig. 2.

Fig. 10 is a fragmentary exterior view

thereof with parts in section, illustrating the construction.

As shown on the drawings:

The reference numeral 1, indicates as a whole a boiler setting for a conventional type of return tubular boiler 2. The furnace into which fuel is introduced for combustion, is denoted by the reference numeral 3, and situated at the exterior of the boiler setting at a point convenient to the source of fuel supply is a fuel mixer, denoted as a whole by the reference numeral 4. Said fuel mixer, as shown in detail in Fig. 2, is provided with a fuel inlet pipe 5, for powdered fuel, and the fuel entering through said pipe 5, passes into a chamber 6. Secured transversely within the chamber 6, is a stationary grid plate 7, and slidably thereover is an adjustable grid plate 8, which, in Fig. 2, is shown closing the grid plate 7, so as to prevent the passage of fuel therethrough. The grid plate 7, rests upon lugs 9, formed on a spider 10, having sharp edged arms, as shown clearly in Figs. 2 and 4, the said lugs being recessed at a distance from the inclosing casing to support the grid plate 7, which is of less diameter than the interior of the casing, so that the periphery of said stationary grid plate 7, over which the grid plate 8 moves, is spaced from the interior wall of the fuel mixer casing so that fuel cannot accumulate therearound and prevent adjustment of the grid plate 8.

Threaded for adjustment through the center of the spider 10, is a pivot or center bearing 11, for the lower end of a vertical shaft 12, which is journaled through the top wall of the mixer casing and is slidably adjustable in its bearing. A longitudinal oil hole 13, is provided through said shaft whereby a lubricant may be introduced through the upper end thereof for the pivot bearing support 11. Secured upon the lower end of said shaft 12, is a rake member 14, comprising four radial arms having teeth formed on the upper and under sides thereof, as shown in Figs. 2 and 7, the teeth of adjacent arms being staggered, so that by rotation of said rake member, the powdered fuel is distributed evenly over the grid plates 7-8, and prevented from accumulating thereon.

Feathered upon the upper end of the shaft 12, on the exterior of the fuel mixer casing, is a worm gear 15, meshing with a worm 16, which is secured upon a drive shaft 17, journaled upon the upper end of the fuel mixer casing, and provided with a wheel 18, to receive a power drive from any suitable source. Formed on the lower end of the mixer 4, is an obliquely directed pipe or passage 19, into which the powdered coal, passing through the grid plates 7 and 8,

falls, and tends to flow to the lower or outlet end thereof by gravity.

A compressed air supply pipe, having a controlling valve 21, is connected to the upper end of the oblique pipe 19, so that the air, as it passes the chamber under the grid plate 7, will tend to create a suction to facilitate introduction of the pulverized fuel. The amount of coal fed into the obliquely directed pipe section 19, is regulated by the adjustment of the grid plate 8 on the grid plate 7, and the grid plate 8, is adjusted by means of a hand wheel 22, having a threaded shaft which has threaded connection with an extension 23, of the grid plate 8, so that rotation of the hand wheel causes a sliding adjustment movement of the grid plate 8, either into open or closed relation with the grid plate 7. Pivotal mounted in the lower end of the oblique pipe section 19, are four vanes or blades 24, which are pivoted on radial axes, and at the free end of each vane is a pin 25, projecting through a curved slot 26, provided in the wall of the pipe section 19.

Rotatably mounted on the exterior of the pipe section 19, in a groove provided therefor, is a collar or ring 27, provided with oblique slots or grooves 28 on the inner face thereof, one of which is shown in Fig. 10, there being one slot for each of the pins 25, whereby rotational adjustments of said ring or collar will cause a pivotal adjustment of the vanes 24, into different angular positions within the pipe section 19. The purpose of said vanes is to impart a spiral flow to the air and powdered fuel blown therebetween as it passes from the pipe section 19 for thoroughly distributing the pulverized fuel in the air. Connected to the outlet end of the oblique pipe section 19, of the mixer, is a conveyer pipe 29, which leads downwardly and through the boiler setting 1, at the rear end thereof, passing along beneath the boiler so as to be subjected to the heat of the combustion of the fuel in the furnace 3, and after passage through the boiler combustion chamber and furnace 3, emerging through the front wall of the boiler setting. Connected into said conveyer pipe 29, on the exterior of the boiler setting prior to entrance of the conveyer pipe thereinto, is a stream jet ring 30, shown in detail in Fig. 6, consisting of a pipe section with a series of small apertures arranged circumferentially around the pipe section and communicating with a peripheral passage 31, extending around the section 30, and a steam supply pipe 32, is connected to this passage 31. A control valve 33, is provided in the steam supply pipe 32, to regulate the quantity of steam admitted into the conveyer pipe 29. The conveyer pipe 29, after it passes through the front wall of the boiler setting

1, is bent back as shown in Fig. 1 and communicates into a nozzle shaped shell 34, of an injector. Connected to said shell 34 is an air supply pipe 35, controlled by a valve 36, through which air, preferably under pressure, is introduced into the combustion chamber 3, simultaneously with the products from the pipe 29.

The operation is as follows:

10 The powdered coal is received from any suitable source in the inlet pipe 5, of the mixer 4, and after flowing downwardly upon the grid plates 7-8, is agitated thereover by the revolving arms of the rake member 14, the teeth of the arms being preferably knife edged as shown in Fig. 2. The opening through the grid plates 7-8, is regulated by the hand wheel 22, to permit the desired quantities of fuel to pass 20 through the mixer. The powdered fuel then flows downwardly into the obliquely directed pipe section 19, of the mixer, and is there taken up by the air passing through the pipe 20, the quantity of air being controlled by the valve 21. In order that the fuel and air may be thoroughly intermixed, the vanes 24, are provided which may be set to deflect the air and pulverized fuel spirally and prevent settling of the fuel in 30 portions of the pipe and at a point farther along in the pipe 29, a spray of steam is admitted into the mixture at the pipe connection 30.

The mixture of steam, air and powdered fuel, which is carried in suspension at high velocity through the conveyer pipe 29, is next subjected to the intense heat of combustion of the fuel beneath the boiler 2, the conveyer pipe 29, extending through the combustion chamber and furnace of the setting so that the contents of the conveyer pipe 29, are heated to a high degree. This causes a distillation of gas from the powdered fuel, and in the presence of the steam 45 which has been admitted into the conveyer pipe, a highly combustible fuel mixture is obtained. This mixture flows into the injector 34, where a further quantity of air preferably under pressure is supplied, assuring the flow of fuel from the outlet of the conveyer pipe 29, and supplying additional air for combustion of the mixture, so that the mixture actually flashes into flame when admitted into the furnace chamber.

The amount of steam admitted to the fuel mixture is governed by the control valve 33, and the additional supply of air under pressure provided at the injector 34, 50 is controlled by the valve 36. It is evident, therefore, that all the components of the fuel mixture may be regulated to the desired extent to secure the most efficient operation of the fuel burning apparatus.

In some instances the operation may be permitted to take place without the addition of steam particularly if the powdered fuel is damp as the water absorbed by the fuel will be converted into steam during passage through the heated conveyer pipe.

I am aware that the details of construction may be varied through a wide range without departing from the principles of this invention, but I purpose claiming broadly the process of burning fuel by flashing the same in the furnace after a certain preliminary treatment.

I claim as my invention:

1. The process of burning fuel, which consists in mixing powdered fuel with air, 80 then subjecting the mixture to an intense heat, then mixing an additional supply of air therewith, and thereafter introducing the mixture into a furnace chamber for combustion.

2. The process of burning fuel, which consists in introducing a powdered fuel into a blast of air under pressure, then admitting steam into the mixture, then subjecting the mixture to an intense heat, and thereafter 90 discharging the mixture together with an additional supply of air into a furnace for combustion.

3. A fuel supply apparatus, comprising a conduit having an outlet at one end, means 95 for supplying air thereto near its inlet end, supplemental air supply means at the outlet end thereof, means for heating a portion of said conduit intermediate its ends, and means for supplying pulverized fuel to 100 said conduit intermediate its inlet end and its heated portion.

4. A fuel supply apparatus, comprising a conduit having an outlet at one end, means for supplying air thereto at its inlet end, 105 supplemental air supply means at the outlet end thereof, means for heating a portion of said conduit intermediate its said ends, means for supplying pulverized fuel to said conduit intermediate its inlet end 110 and its heated portion, and means for supplying steam to said conduit intermediate its fuel inlet and its heated portion.

5. A fuel supply apparatus, comprising a mixer, means for controlling the flow of 115 powdered fuel therethrough, air pressure means communicating with the outlet from said mixer, a conveyer pipe communicating with said outlet, means for introducing steam into said conveyer pipe, and an injector with which said conveyer pipe is connected to supply air under pressure at the point of discharge of the fuel from said pipe.

6. A fuel supply apparatus, comprising 120 a mixer adapted to regulate the flow of powdered fuel, a conveyer pipe to receive the same, means for forcing the fuel under

- air pressure through said conveyer pipe, means for introducing steam into said conveyer pipe, means for heating said conveyer pipe after the introduction of the air, 5 powdered fuel and steam thereinto to generate gas, and an injector at the outlet end of said conveyer pipe for supplying additional quantities of air under pressure.
7. A fuel burning system, comprising the combination with a boiler, and its furnace and combustion chamber, of a conveyer pipe, means for introducing powdered fuel, air and steam thereinto, said conveyer pipe extending through the combustion chamber 10 and furnace of the boiler to subject the contents of said pipe to the heat thereof for the generation of gas, and an injector to supply air under pressure at the point of injection of the contents of said conveyer 15 pipe into the furnace of the boiler.
8. In an apparatus for preparing pulverized fuel for combustion, the combination of a conduit, means for supplying vapor and
- pulverized fuel to said conduit, an adjustable deflector in said conduit adapted to impart a spiral movement to the vapor and fuel, and means for changing the pitch of said deflector. 25
9. In an apparatus for preparing pulverized fuel for combustion, the combination of a conduit, a vapor supply means communicating with said conduit, a casing communicating with said conduit and having a pulverized fuel supply inlet thereto, a perforated valve for controlling the admission of pulverized fuel to said conduit, and a continuously movable agitator adjacent the valve for distributing the pulverized fuel evenly through said valve. 30
- In testimony whereof I have hereunto 4 subscribed my name in the presence of two subscribing witnesses.

NAPOLÉON F. X. BEAUREGARD.
